(57) **CLAIM**

The ornamental design for a hook keeper set, as shown and described.

DESCRIPTION

FIG. 1 is a perspective view showing my new hook keeper design in context of a tie-down strap with the hook keeper in use keeping the tie-down strap hooks positioned relative to structural members and with a hook keeper of my design being shown at each of two opposing ends of the tie-down strap;

FIG. 2 is substantially the view of FIG. 1 with the hook keeper set not in use;

FIG. 3 is an enlarged fragmentary perspective view showing my new hook keeper set design in context and with the hook keeper in use keeping the tie-down strap hook positioned relative to a structural member;

FIG. 4 is an enlarged fragmentary perspective view that is opposite to the view of FIG. 3 and with the hook keeper set not in use;

FIG. 5 is a side elevational view of my new hook keeper set design in context and with the hook keeper in use, the opposing side elevational view being a mirror image thereof; and,

FIG. 6 is the view of FIG. 5 with the hook keeper set not in use.

The broken line showing of a tie-down strap and elements therefor is for illustrative purposes only and forms no part of the claimed design.
